UNITED STATES PATENT OFFICE.

CLIFFORD H. OAKLEY, OF TRENTON, NEW JERSEY, ASSIGNOR TO ESSEX RUBBER COMPANY, OF TRENTON, NEW JERSEY, A CORPORATION OF NEW JERSEY.

DESIGN FOR A SHOE SOLE.

Application filed May 9, 1929. Serial No. 31,155. Term of patent 14 years.

To all whom it may concern:

Be it known that I, CLIFFORD H. OAKLEY, a citizen of the United States, residing at Trenton, in the county of Mercer and State of New Jersey, have invented a new, original, and ornamental Design for Shoe Soles, of which the following is a specification, reference being had to the accompanying drawing, forming part thereof.

Figure 1 is a bottom plan view of a shoe sole showing my new design, and Figure 2 is a section on the line 2—2 of Figure 1.

I claim:

The ornamental design for a shoe sole as shown.

CLIFFORD H. OAKLEY.
